UNITED STATES PATENT OFFICE

126,244

DESIGN FOR AN ELECTRIC RAZOR

Harry Lampert, Los Angeles, Calif.

Application October 28, 1949, Serial No. 96,145

Term of patent 7 years

To all whom it may concern:

Be it known that I, Harry Lampert, a citizen of the United States, residing at Los Angeles, in the county of Los Angeles and State of California, have invented a new, original, and ornamental Design for an Electric Razor, of which the following is a specification, reference being had to the accompanying drawing, forming part thereof.

Figure 1 is a side elevational view of an electric razor embodying my design;

Figure 2 is a top plan view of the design shown in Figure 1; and

Figure 3 is a bottom plan view of the design shown in Figures 1 and 2.

The dominant features of my design reside in the portions illustrated in solid lines.

I claim:

The ornamental design for an electric razor, substantially as shown and described.

HARRY LAMPERT.
